UNITED STATES PATENT OFFICE.

ADOLPH C. GILGEN, OF PASSAIC, NEW JERSEY, ASSIGNOR TO THE NEW YORK AUTOMATIC TELEPHONE COMPANY, OF PATERSON, NEW JERSEY, A CORPORATION OF NEW JERSEY.

TELEPHONE-SWITCH-PLUG MECHANISM.

No. 812,491.

Specification of Letters Patent.

Patented Feb. 13, 1906.

Application filed November 25, 1904. Serial No. 234,139.

To all whom it may concern.

Be it known that I, ADOLPH C. GILGEN, a citizen of the United States, residing at Passaic, in the county of Passaic and State of New Jersey, have invented a certain new and useful Improvement in Telephone - Switch-Plug Mechanism, of which the following is a specification.

The invention relates to intercommunicating telephone systems, and more particularly to the switch-plug mechanism through which communication with the desired stations is established.

The object of the invention is to provide a switch-plug mechanism simple in construction and inexpensive to manufacture, in which the contacts shall be automatically kept bright and clean, which shall be freely accessible for inspection and repairs, and which shall be automatically reset by the movement of the receiver-hook or similar switch.

The invention consists in certain novel features and arrangements of parts and in certain details of construction by which the above objects are attained, to be hereinafter described.

The accompanying drawings form a part of this specification and show an approved manner of carrying out the invention.

Figure 1 is a face or front view of a telephone - box equipped with the improved switch mechanism; and Fig. 2 is an interior elevation of the same as seen from the rear, the body of the box appearing in vertical section. Fig. 3 is an elevation corresponding to a portion of Fig. 2, but showing the plugs and their contacts alone and on a larger scale. Fig. 4 is a corresponding horizontal section, including a portion of the box upon which the mechanism is mounted. Fig. 5 is a horizontal section and plan view, on a still larger scale, showing the action of one of the plugs and its contacts; and Fig. 6 is a corresponding section on the line 6 6 in Fig. 5.

Similar letters of reference indicate the same parts in all the figures.

A is an ordinary telephone-box having a hinged door A' and equipped with a transmitter B of any approved construction, a bell C, and buzzer D. A receiver-hook E' is pivoted to the side wall of the box and extends through a slot in the opposite wall, where it is

bifurcated, as usual, to support the receiver E. A spring A³ tends to elevate the hook, as usual, 55 when relieved of the weight of the receiver.

The switch-plug mechanism is mounted on the door A', the latter, with the strips M M and metal ends M³ M³ joining them, forming a casing therefor open on the interior of the box. On each side of a central strip M' of less depth are a series of holes a, extending through the door, and a plate A⁴ thereon, in which are loosely received the plugs N. Ten are shown, five in each series, but the number 65 may be greater or less. All are alike, and a detailed description of one will suffice. The body N of the plug is preferably cylindrical and is guided and supported at the outer end in the plate A⁴. The end protrudes a short 70 distance and is rounded to offer a convenient surface for the finger in pushing the plug inwardly to establish communication with the corresponding station in the circuit. The inner end or head N' is also cylindrical and terminates in a conical point or end N². Between the portions N and N' the plug is of smaller diameter, forming a neck N³ and two annular shoulders N⁴ N⁵ at the junction with the body and head, respectively. The inner 75 end of the plug is guided in a notch m in a metal strip M², secured one on each side to the central strip M', matching to and receiving the neck N³ and limiting the endwise movement of the plug in both directions by 80 contacting alternately with the shoulders, while permitting the inner end to be moved away from the central strip. The plug thus 85 loosely mounted is held in the notch by the action of a contact-spring P against its inner end. The spring may be one of a series of similar springs formed of a single piece of metal secured beneath the strip M, electrically connected to the metal ends M³, joining the ends of the wood strips M M and M' and 90 serving as a means for attaching the strips to the interior face of the door. 95

The contact-spring P inclines toward its plug and carries on its free end an angular shoulder P', terminating in a reversely-extending flat tooth or contact-point P², adapted when forced outwardly by the plug to make a sliding or wiping contact with its adjacent contact-clip R, forming one of a series of clips mounted on the strip M.

The coaction of the shoulder P' and the an-

nular angular shoulder at the junction of the conical end N^2 and head N' is an important feature of the invention. These parts are so proportioned relatively to the axial movement permitted by the notch m that when the plug is in the inoperative position, as shown at the right in Fig. 4, the shoulder P' rests upon the conical end, exerting the force of the spring P to hold the plug to the notch 5 in such reset or retracted condition and with its point P^2 out of contact with the clip R . In pushing the plug inwardly the spring P is forced toward its clip by the action of the conical end N^2 upon the shoulder P' until at 10 the completion of the inward movement the shoulder P' rides over the angular shoulder on the head N' and lies against the cylindrical portion thereof, as indicated at the left in Fig. 4 and in the full lines of Fig. 5, still acting 15 in the direction to maintain the neck N^3 in its notch and holding the plug frictionally against endwise movement. In this position of the parts the contact-point P^2 has been slid along on the edge of its clip and connection 20 thus made.

It will be noted that the plugs are held in place in both positions by the yielding force of the contact-springs alone, requiring but few parts, and thus permitting highly economical construction, and the open character of the casing allows free access to all the parts when the door A' of the box is swung open. The plugs are inexpensively made from rods of the proper diameter, and the 30 contact-springs and clips are struck from sheet metal by suitable dies.

The plugs are retracted by the action of the shoulder P' on the conical end N^2 ; but it is necessary to initiate such action by moving 40 the plug axially far enough to bring the angular shoulder on the head N' under the influence of the shoulder P' and permit it to act camwise on the conical end. This is effected by two reset bars S , one for each row of 45 plugs, mounted between the rows. Each consists of a bar or strip of metal extending parallel with the strip M' and above or beyond the metal strip M^2 thereon and pivoted at each end at s in the metal ends M^3 M^3 of 50 the casing in such relation to the heads N' as to be turned thereby into a position in which the edge of the reset bar will project beyond the edge of the metal ends when either plug of a series is pushed inwardly and adapted 55 when partially revolved on its pivots s toward the plugs to strike any of the heads presented in its path and force them toward their contact-springs P partially out of their notches m and also axially outward sufficiently to permit the shoulders P' to act and 60 complete the resetting movement. This partial revolution toward the heads is produced by a curved spring secured transversely of the receiver-hook E' , forming two spring- 65 arms E^2 E^2 , riding at their free ends upon the

edges of the metal ends M^3 . When the receiver-hook is in the depressed condition, the arms E^2 overlap diagonally the ends of the reset bars, and the act of pushing in a plug causes the reset bar to assume a position parallel with the adjacent face of the plug and in opposition to the spring-arm E^2 , which is thus forcibly raised, and by its action on the flat edge of the reset bar holds the latter in such position. On removing the receiver the 70 spring A^3 asserts itself and raises the hook, causing the spring-arm E^2 to slip from the flat edge of the reset bar and assume a central position, as indicated by the dotted lines in Fig. 2, and lie parallel with and between the reset bars. The replacing of the receiver depresses the hook and causes the arms E^2 E^2 to sweep along the edges of the metal ends M^3 in opposite directions and engage either 75 or both reset bars presented and force them 80 against the heads of the plugs. Thus the plugs are automatically reset by the act of hanging up the receiver and the whole conditioned for the next call.

Another important end attained by the 90 mechanism is the cleaning effect of the edge of the contact-clip R against the surface of the tooth or point P^2 . As before described, the inward movement of the plug through its conical end N^2 forces the contact-spring P toward its clip, and the surface of the point P^2 is caused to wipe across the edge of the clip, 95 tending to insure a clean bright surface best adapted for high conductivity. This cleaning action is still further extended by the resetting movement. The reset bar forces the plug away from the central strip, as indicated by the heavy dotted lines in Fig. 5, causing the point P^2 to travel still farther upon the edge of the clip and until the shoulder P' 100 passes from the head N' to the conical end N^2 of the plug and the contact-spring drives the plug to the original or inoperative position, 105 as shown at the right in Fig. 4 and in light dotted lines of Fig. 5. Thus each setting and resetting causes the point P^2 to wipe across the sharp edge of the clip. The scraping action of the latter upon the surface of the point P^2 extends not only to the line on such 110 surface to which such edge reaches in making contact, but also as much farther as is caused by the further movement of the point in the resetting movement, and a clean scraped surface at the point or line of normal contact is 115 thus assured.

M^4 is a stop located on the strip M' between the reset bars to prevent the latter approaching each other or folding in the wrong direction.

The connections at all the stations are similar and, with the battery-circuits and lines, are the same as the arrangement shown in a prior application, filed by me June 11, 1904, Serial No. 212,104, Patent No. 785,728, with which the herein-described switch-plug mech- 125 130

anism is especially designed to serve, although it will be understood it may be employed successfully with other systems and arrangements of circuits.

5 I claim—

1. In a switch-plug mechanism, a plug having a conical end, and a contact-spring having a portion disposed in the path of and constructed to engage said plug frictionally and hold said plug when the latter is moved in one direction and to act upon said conical end to complete the return movement of said plug.

15 2. In a switch-plug mechanism, a plug having a conical end, a contact-spring having a portion disposed in the path of and constructed to engage said plug frictionally and hold said plug when the latter is moved in one direction and to act upon said conical end to 20 complete the return movement of said plug, and means for initiating such return movement.

25 3. In a switch-plug mechanism, a plug having a conical end, a contact-spring having a portion disposed in the path of and constructed to engage said plug frictionally and hold said plug when the latter is moved in one direction and to act upon said conical end to complete the return movement of said plug, 30 and means operated by a receiver-hook or analogous switch for initiating such return movement.

35 4. In a switch-plug mechanism, a plug having a cylindrical head and conical end, means for initiating the return movement of the plug, and a contact-spring having a portion disposed in the path of and constructed to engage frictionally with said head and hold said plug when the latter is moved in one direction and to act upon said conical end to 40 complete the return movement of said plug, and means for making and breaking an electric circuit through the movements of said spring.

45 5. In a switch-plug mechanism, a plug having a cylindrical head and conical end, a contact-spring having a portion disposed in the path of and constructed to engage frictionally with said head and hold said plug when the latter is moved in one direction and to act upon said conical end to complete the return movement of said plug, means for initiating such return movement, and means for making and breaking an electric circuit through 50 the movements of said spring.

55 6. In a switch-plug mechanism, a plug having a cylindrical head and conical end, a contact-spring having a portion disposed in the path of and constructed to engage frictionally with said head and hold said plug when the latter is moved in one direction and to act upon said conical end to complete the return movement of said plug, means operated by a receiver-hook or analogous switch for initiating such return movement, and means 60

for making and breaking an electric circuit through the movements of said spring.

7. In a switch-plug mechanism, a plug having a cylindrical head and conical end, a contact-clip, a contact-spring having a portion disposed in the path of and constructed to engage said head frictionally and hold said plug when the latter is moved in one direction and also contact with said clip, and to act upon said conical end to complete the return movement of said plug and break such contact, and means for initiating such movement.

8. In a switch-plug mechanism, a series of plugs having each a cylindrical head and conical end, a contact-clip for each plug, a contact-spring for each plug having a portion disposed in the path of and constructed to engage said head frictionally and hold said plug when the latter is moved in one direction and also contact with its clip, and to act upon said conical end to complete the return movement of said plug and break such contact, a reset bar adapted to act on said heads to initiate such return movement, and means for actuating said reset bar.

9. In a switch-plug mechanism, a series of plugs arranged in a row, each having a cylindrical head and conical end, a corresponding series of contact-springs each bent upon itself to form an angular shoulder and a contact-point, a series of contact-clips one adjacent to each of said contact-points, the said shoulder adapted to engage the head of its plug frictionally and hold said plug when the latter is moved in one direction and with its contact-point in wiping contact with its contact-clip, and to break such contact and act upon said conical end to complete the return movement of said plug, a reset bar extending along said row of plugs and adapted to act on said heads to initiate such return movement, and means carried by the receiver-hook or analogous switch adapted to actuate said reset bar.

10. In combination with a telephone-box having a receiver-hook, a series of plugs loosely mounted in the casing of said box and extending into the interior thereof, each of said plugs having a cylindrical head and a conical end, a contact-clip for each plug, a contact-spring for each of said plugs adapted to engage said head frictionally and hold its plug when the latter is thrust toward the interior of said box and make contact with its clip, and to break such contact and act upon the conical end of its plug to complete the return movement of said plug, a reset bar arranged adjacent to said series of plugs and adapted by its movement to initiate such return movement, and a spring-arm carried by said receiver-hook and adapted to move said reset bar when said receiver-hook is depressed.

11. In combination with a telephone-box having a receiver-hook, two series of plugs loosely mounted in the casing of said box in

- parallel rows and extending into the interior of said box, each of said plugs having a cylindrical head and conical end, two series of contact-clips one clip for each plug, two series of contact-springs, one spring for each plug, each of said contact-springs adapted to engage the head of its plug frictionally and hold said plug when the latter is thrust toward the interior of said box and make contact with its clip, and to break such contact and act upon the conical end of its plug to complete the return movement of said plug, two reset bars, one for each series of plugs, each adapted by its movement to initiate such return movement of any plug of its series, and spring-arms carried by said receiver, adapted when said receiver-hook is raised to lie between said reset bars and to move the latter when said receiver-hook is depressed.
12. In a switch-plug mechanism, a plug arranged to be moved axially, a contact-clip, a contact-spring in the path of said plug and adapted to be moved aside by said plug into wiping contact with said clip, and means in the path of said plug and pivoted for moving said plug laterally toward said clip, whereby the extent of said wiping movement is increased.
13. In a switch-plug mechanism, a plug arranged to be moved axially, a contact-clip, a contact-spring in the path of said plug and adapted to be moved aside by said plug into wiping contact with said clip, and means for inducing a return movement of said plug and also moving said plug laterally toward said clip, whereby the extent of such wiping movement is increased.
14. In a switch-plug mechanism, a series of plugs, a contact-spring for each plug, and a contact-clip for each spring, the latter adapted to be moved into contact with its clip by an endwise movement of its plug, a reset bar common to all the plugs in said series, a receiver-hook or analogous switch, and a spring-arm carried by said hook, the construction and arrangement being such that when said hook is depressed and a plug pushed in said reset bar will be held in an inoperative position, when said hook is elevated, said bar will be released, and when said hook is again depressed, said reset bar will be moved in the direction to induce a return movement of said plug.
15. In a switch-plug mechanism, two series of plugs arranged in two parallel rows, a contact-spring for each plug and a contact-clip for each spring, the latter adapted to be moved into contact with its clip by an endwise movement of its plug, two reset bars each common to all the plugs of one series, a receiver-hook or analogous switch, and oppositely-extending spring-arms thereon, each of said arms adapted to actuate one of said reset bars.
16. In a switch-plug mechanism, a receiver-hook having a spring-arm, a plug adapted to be moved axially, a contact-clip, and a contact-spring, the said contact-spring serving to hold said plug frictionally at one end of its movement and to make contact with said clip, and to complete the return movement of said plug and to break such contact, and a reset bar actuated by said spring-arm, arranged to strike said plug and initiate such return movement by the depression of said receiver-hook.

In testimony that I claim the invention above set forth I affix my signature in presence of two witnesses.

ADOLPH C. GILGEN.
